DESIGN FOR A COMBINED DISPLAY STAND AND CONTAINER FOR PERFUMERY

Louis J. Misuraca, Glendale, Calif.

Application July 25, 1944, Serial No. 114,548

Term of patent 14 years

(Cl. D80—9)

To all whom it may concern:

Louis J. Misuraca, a citizen of the United States and a resident of Glendale, in the county of Los Angeles, State of California, has invented a new, original, and ornamental Design for a Combined Display Stand and Container for Perfumery, of which the following is a specification, reference being had to the accompanying drawing, forming part thereof, and in which

Fig. 1 is a perspective view of a combined display stand and container for perfumery showing my new design;

Fig. 2 is a top plan view of same; and

Fig. 3 is a sectional view on line 3—3 of Fig. 2.

I claim:

The ornamental design for a combined display stand and container for perfumery, as shown.

LOUIS J. MISURACA.
